UNITED STATES PATENT OFFICE.

SAMUEL CLIFFORD FORRESTER, OF ATLANTA, GEORGIA, ASSIGNOR TO FULTON BAG
AND COTTON MILLS, OF ATLANTA, GEORGIA.

MOUNTING FOR FLEXIBLE PLATES FOR FLAT-BED PRESSES.

Application filed September 12, 1921. Serial No. 499,921.

To all whom it may concern:

Be it known that I, SAMUEL CLIFFORD FORRESTER, a citizen of the United States, residing at Atlanta, in the county of Fulton 5 and State of Georgia, have invented new and useful Improvements in Mountings for Flexible Plates for Flat-Bed Presses, of which the following is a specification.

This invention relates to a device for holding printing plates in proper position for printing on flat-bed presses; more especially, it is directed to an improved form for suitably mounting elastic printing elements.

One of the fundamental principles of this 15 invention is the provision of an improved form possessing facilities for detachably securing an elastic printing element in operative position on the form, the mounting being such as to permit interchangeability 20 of the printing element for either flat-bed or rotary work.

Another important object of this invention, is to produce a form for the use of elastic printing elements which will enable 25 the latter to be expeditiously mounted and adjustably tensioned in order to obtain the same degree of distortion of the printing element when mounted on a flat-bed press as prevailed when mounted on a rotary press.

30 Other important objects of this invention are: to provide a form which may be prepared and made ready for printing with a minimum loss of time, and one which will accommodate a plurality of printing elements 35 on a single mounting, and likewise enable the removal of one or more of the printing elements without disturbing the others.

With these and other objects in view, 40 which will become apparent as the description proceeds, the invention resides in the construction, combination and arrangement of parts, hereinafter more fully described and claimed, and illustrated in the accompanying drawings, in which like characters 45 of reference indicate like parts throughout the several figures, of which:

Fig. 1 is a perspective view of this improved mounting illustrating the series of 50 printing elements in operative position.

Briefly stated, this improved form includes parallel side-sticks suitably spaced with "printer's furniture" and bridged by elastic printing elements engaged along 55 their edges by fastening means seated in

said side-sticks, the assembled form after the plates have been properly tensioned, being suitably locked in a standard chase.

When printing on loosely woven fabrics such as burlap, jute, and the like, and especially when the design to be printed involves two or more colors, it is frequently necessary to print one color of the design with a rotary press and the other color or colors with a flat-bed press. Heretofore, it has been the custom in multi-color printing to employ separate printing elements, the form of plate depending on the character of press employed. But this arrangement has been found highly unsatisfactory, owing to the difficulty experienced in securing proper registration of the colors, as well as requiring a multiplicity of plates and operations.

It is, therefore, the aim and purpose of this invention to provide a form by means of which the elastic element used on a rotary press may be transferred from the latter and employed for flat-bed work, or vice versa, and when so transferred may be tensioned so as to give characters on the printing element the same degree of distortion when used on a flat-bed press, as existed when in use on a rotary press.

In the illustrated embodiment characterizing this invention there is shown a standard chase 5, interior of which, and parallel to the sides thereof are positioned spaced side-sticks 6 and 7. Located between these side-sticks are a plurality of blocks 8 of varying dimensions, known as "printer's furniture", forming in conjunction with the side-sticks, a rectangular block or bed surface upon which are positioned the printing elements or plates 9. This structure is locked in the desired position within the chase by means of the usual quoins 10, positioned intermediate one of the side-sticks and the side of the chase.

Side-sticks 6 and 7 are provided with a plurality of apertures 11 to receive screws 100 12, the free ends of which are adapted to extend through suitable openings or grommets 13 formed at intervals along the edges of the printing plate or plates 9, the dimensions of said grommets being such as to readily receive the heads of the screws 12.

Although in the illustrated embodiment screws are shown for the securement of the printing element, it may be found expedient to substitute snap-fastening means similar 110

to those used as glove clasps, so that the printing plate may be readily snapped into position.

The structural features of this improved form having been described, its assemblage is as follows: The side-sticks being suitably spaced with printers' furniture to the approximate width of the printing elements, the edges of the latter are then brought into engagement with the screws seated in the side-sticks, additional furniture is then added to tension the printing element, whereupon the form is suitably locked in the chase. A proof is then run off to ascertain if the characters of the printing element have been sufficiently distorted to give the desired registration; if not, the form is removed and additional furniture is interposed between the side-sticks to further stretch the printing element to distort the characters sufficiently to obtain the desired registration.

Manifestly, with this arrangement it is possible to interchangeably employ an elastic element on rotary or flat-bed presses according to the exigencies of the situation, to quickly attach or detach the printing element and to readily stretch the same to any desired degree.

Although in the foregoing, certain elements may have been set forth as best adapted to perform the functions allotted to them, nevertheless, it is to be understood that various minor changes as to form, substance, etc., may be resorted to within the scope of the appended claims without departing from or sacrificing any of the principles of this invention.

Having thus described my invention, and without enumerating variations and equivalents, what I desire protected by Letters Patent is as set forth in the following claims:

1. A form including spaced side-sticks and an elastic printing element interconnecting said sticks.

45 2. A form including spaced side-sticks and an elastic element interconnecting said sticks, and means effecting a detachable connection between the printing element and the side-sticks.

50 3. A form including spaced side-sticks, a base intermediate the side-sticks, a printing element overlying the base and detachably connected to the side-sticks.

4. A form including spaced side-sticks, 55 a base intermediate the side-sticks, and an elastic printing element overlying the base and detachably connected along its edges to the side-sticks.

5. A form including spaced side-sticks, 60 printer's furniture intermediate the side-sticks forming a printing base, and an elastic printing element overlying the base and detachably connected to the side-sticks.

6. A form including spaced side-sticks, 65 printer's furniture intermediate the side-

sticks forming a printing base, and an elastic printing element overlying the base and detachably connected at its edges to the side-sticks.

7. A form including spaced side-sticks, 70 printers' furniture intermediate the side-sticks, an elastic printing element bridging the side-sticks and overlying said furniture, and cooperating means along the edges of said flexible element and on said side-sticks 75 effecting a detachable connection between the latter and the flexible printing element.

8. A form including spaced side-sticks, 80 an elastic printing element interconnecting the side-sticks, and means intermediate the side-sticks for tensioning said printing element.

9. A form including spaced side-sticks, 85 an elastic printing element interconnecting said side-sticks and detachably connected at its extremities to the latter, and means intermediate the side-sticks for tensioning said printing element.

10. A form including spaced side-sticks, 90 an elastic printing element interconnecting said side-sticks, and printer's furniture interposed between the side-sticks to tension the printing element and provide a printing base.

11. A form including spaced side-sticks, 95 an elastic printing element interconnecting said side-sticks and detachably connected at its extremities to the latter, and printer's furniture interposed between the side-sticks to tension the flexible element and provide 100 a printing base.

12. The combination with a chase; of a form including spaced side-sticks, printer's furniture intermediate said sticks forming a printing base, and an elastic printing element overlying the base and detachably connected to the side-sticks.

13. The combination with a chase; of a form including spaced side-sticks, printer's furniture intermediate said sticks forming a printing base, and an elastic printing element overlying the base and detachably connected at its extremities to the side-sticks.

14. The combination with a chase; of a form including spaced side-sticks, an elastic printing element interconnecting the side-sticks, and means intermediate the side-sticks for tensioning said printing element.

15. The combination with a chase; of a form including spaced side-sticks, an elastic printing element interconnecting said side-sticks and detachably connected at its extremities to the latter, and means intermediate the side-sticks for tensioning said 120 printing element.

16. The combination with a chase; of a form including spaced side-sticks, an elastic printing element interconnecting said side-sticks and detachably engaged at its extrem- 130

ties with the latter, and printer's furniture interposed between the side-sticks to tension the flexible printing element and provide a printing base.

5 17. The combination with a chase; of a form including spaced parallel side-sticks, an elastic printing element interconnecting said side-sticks and detachably engaged at its extremities with the latter, and printer's furniture interposed between the side-sticks to tension the flexible printing element and provide a printing base.

10 18. In a mounting of the character described, the combination with a chase, of spaced parallel side-sticks arranged in the chase adjacent opposite longitudinal sides

of the latter, a plurality of elastic printing plates bridging the space between the sticks with their opposite edges engaging the latter, said plates being adjustable longitudinally of the sticks, spacer elements between the said sticks, means for locking the said sticks within the chase, and means for fastening the said plates to the said sticks, said means embodying separable fastening elements carried, respectively, by the said sticks and the said plates. 20 25
